UNITED STATES PATENT OFFICE.

ADOLPHE BRÉCHOT, OF PARIS, FRANCE.

REFUSE-DESTRUCTOR FURNACE.

Application filed September 30, 1919. Serial No. 327,492.

To all whom it may concern:

Be it known that ADOLPHE BRÉCHOT, citizen of the French Republic, residing at 7 Rue de Lille, Paris, Seine, in the Republic of France, has invented certain new and useful Improvements in Refuse-Destructor Furnaces, of which the following is a specification.

The present invention has for its object 10 a furnace for the destruction of refuse or the combustion of materials such as turf, etc. provided with improvements which permit of rendering the use thereof simple, convenient and economical.

These results are obtained principally by 15 means of a special arrangement of grate with walls which are widened towards the bottom, and which permit of the instantaneous discharge of the burnt materials being effected without effort, by means of a grid 20 composed of two rocking balanced parts which can be worked simultaneously. The furnace has also an arrangement by which the greater portion of the units of heat still 25 contained in the materials thus discharged is recovered.

The description about to be given with 30 reference to the accompanying drawing which is given by way of example, relates to a method of practically carrying out the invention of which it will render the peculiarities and advantages properly understood.

Figure 1 is a vertical section from front 35 to back of the furnace constructed according to the invention.

Figure 2 is a transverse section of its left hand part, and a semiend view of its right hand part.

The furnace represented in these figures 40 is formed of a chamber *a*, in the interior of which is a block of masonry *b* of a form suitable for leading away the products of combustion, a bridge *c*, a grate *d* and a discharging chamber *g*.

The chamber *a* is open at its upper part 45 at *e*. This opening serves for charging and is surmounted at pleasure by an inclined chute formed by a register or any other suitable and well known charging arrangement.

It opens above the bridge *c* which is of some refractory material and on to which are tipped first the materials to be burnt in order to subject them to a partial drying.

Between this bridge *c* and the grate *d* is

a space in the form of a hopper, comprised between the inclined walls *e*², *e*³ (see Figure 2), and through which the materials to be destroyed descend on to the grate at the desired moment.

The grate *d* is formed by a metal box *f* through which air is circulated by means of a fan, the air being fed to the box by a pipe *g* connected to a collector *h* placed in a vaulted chamber *i* and supplying a whole battery of furnaces placed side by side. The hollow box *f* has a double purpose. It serves to heat up the air to support combustion and also prevents by the cooling which results from the passage of the air over the inner walls which constitute the grate, the sticking of the materials or burnt clinkers to the grate.

The discharge of these materials is thus 50 carried out with facility, but it is rendered still more complete by the special inclination of the walls of the grate. These are widened from the top downwards in such a way as to form an inverted hopper, both on its side faces as well as on its transverse faces. In the front transverse face however, there is an interruption of the inclined wall and also of the hollow box so as to form an opening corresponding to the door *j* placed in the front of the furnace for the purpose of inserting the first charge of fuel 55 which is ignited to start the fire at the outset.

On the other hand, on its external side faces, the box *f* has its profile broken as at *k* which contributes to the stability of the box. The box itself is supported by its front and rear ends which rest on the walls *l* of the lower part of the furnace. In order to ensure the continuity of the support at the front, the open part of the box *f* only descends to near the lower level of the box and a triangular passage *m* is left which connects the two halves.

Each of these halves has an outlet for the air for ventilation, which is directed by the pipe *n* into the rocking piece corresponding thereto forming one of the parts of the grid of the grate.

These rocking pieces are represented respectively at *o* and *o*¹. They are constituted by two hollow identical panels the upper faces of which constitute the bottom of the grate *d*. These faces are pierced along their whole length by holes such as *p*

which are constricted towards the top and which form so many passages for the air coming from the box *f*.

The air supply is adjustable by dampers 5 such as *q* which may be of any kind. The air is admitted to the interior of the panels at their rocking centres by means of a suitable connection, the junctions *n* of which form the internal fixed part which fits into 10 the ends of the hollow trunnions of the pieces *o* and *o*¹. Supports *s* and *s*¹ arranged at both front and back outside the grate receive the trunnions which are able to rotate freely in the masonry portions *l*.

15 Movement may be imparted simultaneously to the two panels by a connection such as that represented in the figures. A wheel *t* is fixed on the outer end of each of the trunnions *r*, and one wheel is connected with the 20 other by a crossed chain *u*. In this way by means of an operating lever *v* attached to one of the wheels *t* simultaneous rotation of these wheels is produced in order to completely release the bottom of the grate.

25 Counter-weights *w* hung on cables wound round pulleys at the rear part balance the masses in motion in such a way that the opening is effected without any great effort. The panels then assume the position indicated by dot and dash lines at *o*² in Figure 2. It will be seen that they are entirely moved out of the way and masked by the lower part of the box *f* the side faces of which overhang the inside of the ashpit. The fixation 35 of the wheels and the grid panels is ensured by means of a system of catches of the ordinary type (not shown).

The ashpit *g*¹ situated below the grate has an inner wall sharply inclined in the direction of a door *x* which affords a passage from this ashpit to an underground gallery from which the discharged products are collected.

40 The side and rear walls of the ashpit are pierced with openings such as *y* which open into a pipe *z* which establishes a communication by which the hot gases evolved from the clinkers and other products of combustion can be directed into the combustion chamber *a*¹, where they pass through openings *b*¹. On another side this combustion chamber receives directly the gases issuing from the furnace through the passages *c*¹ and *d*¹, and the whole is evacuated through 45 rear passages *e*¹ towards apparatus where it is used.

The air after leaving the fan may be suitably preheated before passing into the furnace boxes.

50 The working of this furnace will be easily understood.

The refuse or materials to be burned may be shot by the transport vehicles into a hoist which raises them and delivers them to the charging chute opening above the opening *e*.

From there they fall at desired moments, on to the bridge *c* and the vapours which they evolve pass through the passage *c*¹ into the chamber *a*¹. Three or four times per hour the stoker by the aid of a curved fork which he passes through the door *j*¹ situated above the door *j* draws the refuse from the bridge *c* and causes it to fall on to the grate *d* where he spreads it out through the door *j*. He then opens the damper of the charging chute so that a fresh lot of the refuse contained therein shall fall on to the bridge *c*.

55 The air supplied by the fan after having been, if desired, preheated, enters the box *f* of the furnace through the pipe *g*. In passing through the box, the air also absorbs a certain quantity of the heat from the inner walls of this box and thus cools these walls, and it finally enters the panels of the grate. It will be seen that the vapours from the refuse on the bridge *c*, the smoke and flames from the furnace and the hot gases from the chamber of the ashpit *g*¹ all 60 flow into the combustion chamber *a*¹ whence they pass through the rear passage *e*¹.

About every hour, when the destruction of the refuse is judged to be complete, the stoker actuates his operating lever *v* for the purpose of opening the two panels of the grate. The fused clinker and slag fall into the ashpit without leaving anything sticking to the walls of the furnace. The stoker then immediately closes the grate again by turning his lever in the reverse direction. He then causes the dried refuse to fall from the bridge on the grate, recharges the bridge again and so on. The clinkers are extinguished in the chamber *g*¹ and each time it is desired to effect a fresh discharge by opening the grate, the door *x* is first opened in order to discharge the clinkers and leave room for more.

70 In the construction equivalent sections must naturally be provided for supplying air to the different parts. In particular the total section of the holes *p* in the panels must be practically equal to that of the conduits *n*. The dust which may in course of time collect in the interior of these panels is withdrawn through the corresponding trunnions, but it should be noted that the accumulation of such dust is very rare owing to the ventilation and the density of the materials falling into the furnace.

75 It must be understood also that the above arrangements are in no way limitative, and that the proportions and details of the various parts of the furnace may be varied according to circumstances while yet keeping within the scope of the invention.

80 What I claim and desire to secure by Letters Patent of the United States is:—

85 1. An incinerating furnace comprising, in combination, a block of masonry in which

is formed a chamber, holes in said masonry for charging and discharging purposes, a drying bridge in the interior of the chamber to receive the material to be incinerated 5 which are tipped through the charging hole, a combustion chamber situated beneath the bridge and having inclined walls in the form of a hopper, a grate, the sides of which are formed by a metal box through which air is circulated, the inner walls of said box inclining outwardly from top to bottom, 10 oscillatory hollow panels in the bottom of said grate and provided with holes in their upper faces through which air previously circulated through the metal box is blown into the furnace, said panels having hollow 15 trunnions rotatably supported at each end of the furnace, the outer trunnions communicating with the metal box, a toothed wheel on each of the outer trunnions, a chain connecting the toothed wheels to effect simultaneous rotation of the trunnions and rocking of the grate panels, a lever attached to one wheel for controlling the rocking of the 20 grate panels towards or away from one another, counterweights for balancing said 25 panels, a lower chamber under the grate for collecting the residues of the combustion, and pipes connecting the lower chamber with the combustion chamber for enabling the heat evolved from the residues of the combustion to be utilized.

2. An incinerating furnace comprising, in combination, a block of masonry in which is formed a chamber, holes in said masonry for charging and discharging purposes, a drying bridge in the interior of the chamber to receive the materials to be incinerated which are tipped through the charging 25

hole, a combustion chamber situated beneath the bridge and having inclined walls in the form of a hopper, a grate, the sides of which are formed by a metal box through which air is circulated, the inner walls of said box inclining outwardly from top to bottom, 30 oscillatory hollow panels in the bottom of said grate and provided with holes in their upper faces through which air previously circulated through the metal box is blown into the furnace, said panels having hollow 35 trunnions rotatably supported at each end of the furnace, the outer trunnions communicating with the metal box, a toothed wheel on each of the outer trunnions, a chain connecting the toothed wheels to effect simultaneous rotation of the trunnions and rocking of the grate panels, a lever attached to one wheel for controlling the rocking of the 40 grate panels towards or away from one another, counterweights for balancing said 45 panels, a lower chamber under the grate for collecting the residues of the combustion, and pipes connecting the lower chamber with the combustion chamber for enabling the heat evolved from the residues of the 50 combustion to be utilized.

In testimony whereof I affix my signature.

ADOLPHE BRÉCHOT.
